CLAIM

We claim the ornamental design for a stapler, as shown and described.

DESCRIPTION

FIG. 1 is a front perspective view of a stapler showing our new design.

FIG. 2 is a left side view of the stapler of FIG. 1.

FIG. 3 is a right side view of the stapler of FIG. 1.

FIG. 4 is a front view of the stapler of FIG. 1.

FIG. 5 is a rear view of the stapler of FIG. 1; and,

FIG. 6 is a top view of the stapler of FIG. 1.

The broken lines in the drawings depict portions of the stapler that form no part of the claimed design.

1 Claim, 6 Drawing Sheets
